UNITED STATES PATENT OFFICE.

PHILIP L. McCLURE, OF FORT COBB, OKLAHOMA.

ADJUSTABLE WINDOW-SHADE AND CURTAIN HANGER.

1,059,890.

Specification of Letters Patent.

Patented Apr. 22, 1913.

Application filed September 4, 1912. Serial No. 718,514.

To all whom it may concern:

Be it known that I, PHILIP L. McCLURE, a citizen of the United States, residing at Fort Cobb, in the county of Caddo and 5 State of Oklahoma, have invented new and useful Improvements in Adjustable Window-Shade and Curtain Hangers, of which the following is a specification.

This invention relates to shade roller and 10 curtain pole brackets, the object in view being to provide an adjustable bracket for supporting window shade rollers and curtain poles which will enable said bracket and the parts carried thereby to be adjusted 15 to any desired extent from the top of the window frame, so as to provide for the proper ventilation and illumination over and above the curtain and shade.

A further object of the invention is to 20 provide a device of the kind referred to which may be manufactured at a minimum cost, and readily applied, without the aid of a skilled mechanic.

With the above and other objects in view, 25 the invention consists in the construction, combination and arrangement of parts, as will be hereinafter more fully described, illustrated in the accompanying drawings, and pointed out in the claim hereunto appended.

In the drawings: Figure 1 is a front elevation of a window frame, showing the device of this invention applied thereto. Fig. 2 is a side elevation of the same. Fig. 3 is 35 a detail perspective view of one of the slide brackets. Fig. 4 is a vertical section through the same, showing the detachable pole supporting arm.

In carrying out this invention, I employ 40 parallel guides 1 secured to opposite vertical portions 2 of a window frame, the said guides 1 being of any suitable length and being secured at their top and bottom ends to the window frame. Each of said guides 45 is preferably in the form of a metal strap of suitable width and thickness, having the lower extremity thereof offset inwardly, as shown at 3, and provided with a hole 4 to receive a screw or other fastening device 5. 50 At its upper end, each guide 1 is provided with a hole 6 to receive a screw or other fastener 7 which passes therethrough into the window frame, the upper end of the guide being held at a suitable distance from the 55 window casing by means of an interposed spacing block 8.

Mounted so as to be capable of being slid up and down on each guide 1 is a bracket 9 provided near its top and bottom with two sets of guide embracing fingers, the fingers of each set being located at opposite sides of the bracket body and provided with hook-shaped retaining lips 10 which bear and ride against the rear faces of the guides or straps 1. Each bracket is also provided with a binding screw 11 passing through the front of the bracket and bearing against the front face of the guide 1, thereby enabling the bracket as a whole to be adjusted lengthwise of the guide and securely fastened at 60 any desired point of elevation thereon. The screw 11 bears against the guide or strap, between the top and bottom fingers 10, and is adapted to deflect said guide or strap sufficiently to cause it to bind tightly against 65 the fingers.

In its upper side, each bracket is provided with a vertical socket 12, in which is removably fitted the lower extremity of the shank 13 of a pole supporting arm 14, the 70 upper and outer end portion of which is curved, so as to embrace a curtain pole and hold the same in proper position to support the curtain in front of the window frame. Each bracket is further provided with an 75 outwardly extending ear 15 formed with a hole or slot 16 for the purpose of receiving one of the end pintles of a curtain shade roller, shown at 17.

From the foregoing description, taken in 80 connection with the accompanying drawings, it will now be seen that the roller and pole supporting brackets may be readily adjusted up and down on the parallel guides 1, so as to provide for the required amount 85 of ventilation and light over the shade roller and curtain pole. It will further be seen that the device referred to is exceedingly simple and economical in construction, and the adjustment referred to may be 90 easily effected. Furthermore, the device as 95 a whole may be readily applied to any window frame, without requiring the services of an expert workman.

What is claimed is:

The combination with a window frame, 100 of vertical parallel metal straps terminally fastened in spaced relation to said frame and forming parallel guides, slide brackets movable along said straps and formed in 105 their top faces with downwardly extending sockets, top and bottom sets of strap em-

bracing fingers extending backwardly from the body of the bracket and bearing and riding against the rear sides of said straps, set screws passing through threaded openings in the front sides of the brackets between the top and bottom sets of fingers and adapted to deflect the intervening portions of the straps, shade roller supporting ears on said brackets, and curtain pole support-

ing arms having downwardly extending shanks detachably seated in said sockets in the tops of the brackets.

In testimony whereof I affix my signature in presence of two witnesses.

PHILIP L. McCLURE.
